CUTTER CHAIN

Warren Noble, Michigan City, Ind., assignor to
 Sullivan Machine Company, a corporation of
 Massachusetts

Application November 27, 1934, Serial No. 755,012

18 Claims. (Cl. 262—33)

This invention relates to cutter chains and more particularly to improvements in a cutter bit and bit holding means of a mining machine cutter chain.

5 An object of this invention is to provide an improved mining machine cutter chain. Another object is to provide an improved adjustable positioning and holding means for a cutter bit. A further object is to provide an improved bit holding 10 means for adjusting a cutter bit into different angularly related positions with respect to a bit block whereby but a single form of bit block may be employed to attain all positions of the cutter bit. Yet another object is to provide a cutter bit 15 of an improved design to obtain improved cutting means, and due to its particular shape, greatly improving the distribution of heat at the cutting points. A still further object is to provide an improved bit holding means for positioning 20 a cutter bit in different angularly related positions and end-for-end relations with respect to a bit block. These and other objects and advantages of the invention will, however, herein-after more fully appear.

25 In the accompanying drawing there is shown for purposes of illustration one form which the invention may assume in practice.

In this drawing,—

Fig. 1 is an end elevational view of a bit block 30 with which the illustrative embodiment of the invention is associated.

Fig. 2 is a side elevational view of the bit block shown in Fig. 1, showing the improved cutter bit in position thereon.

35 Fig. 3 is a view in longitudinal section taken substantially on line 3—3 of Fig. 2.

Fig. 4 is a cross sectional view taken on line 4—4 of Fig. 2.

Fig. 5 is an elevational view of the improved 40 bit holder.

Fig. 6 is a perspective view of the improved cutter bit.

In this illustrative embodiment of the invention there is shown a bit block 1, a series of 45 which are adapted to be pivotally connected together by suitable strap links or otherwise to form an endless cutter chain in a well known manner. The bit block 1 has a lateral boss or lug 2 provided with a longitudinal bore 3, the inner periphery of which is serrated at 4. Receivable in the longitudinal bore 3 is the shank 5 of a bit holder 6, the latter herein composed of two mating parts 7 and 8 of semi-circular cross section and cooperating to form the cylindrical shank 5 for 50 reception within the lug bore. The exterior per-

iphery of the shank 5 is toothed at 9 for engagement with the serrations in the lug bore to hold the holder against angular displacement in the bore. In this instance, each part of the bit holder 6 is recessed at 10, and these recesses in the bit holder parts cooperate to form a socket 11 for receiving a cutter bit 12 of improved design.

The cutter bit 12 is herein of the so-called detachable type, preferably stamped out of sheet metal into the desired shape and suitably tempered to attain the desired hardness. The body 13 of this cutter bit is preferably generally V-shape in cross section, and the ends of the body are slabbed off at 14 to form relatively inclined faces lying in the plane sides of an obtuse dihedral angle, these slabbed off ends providing a pair of cutting points 15, 15 at each end of the bit on the same side of the bit, the cutting points being formed on the flanged legs of the V. The bit, due to its particular shape, tends to reduce concentration of heat at the cutting points of the bit, this being a result, in the main, of the relatively thin cross section of the bit body.

The socket 11 in the bit holder is also preferably of generally V-shape for receiving the V-shaped bit body, and the holder parts 7 and 8 have portions 16, 16 projecting within the V-shaped recess in the bit and shaped to conform with the inner contour of the bit. The semi-circular rear end portions of the bit holder parts 30 cooperate to form a bolt-like portion 17, to which is threaded a nut 18 engaging the rear face of the bit block lug. This nut, when tightened, pulls the holder axially rearwardly with respect to the bit block lug to 35 clamp the bit against the forward face of the bit block lug. This bolt-like portion 17 is annularly grooved at 19 for receiving a snap ring 20 to provide an abutment for the nut 18 to prevent inadvertent release of the nut from the bolt.

40 By releasing the snap ring and the nut 18 from the bolt portion 17 of the holder, the latter may be withdrawn forwardly in an axial direction from the lug bore, and the two parts 7, 8 thereof separated to release the cutter bit from its socket. When one cutting end of the cutter bit becomes dull the bit may be turned end-for-end within the holder socket or the bit holder may be turned 180° within the bit block lug bore to present sharp cutting points to the work. When 50 the bit becomes dull it may, due to the inexpensive design, be discarded and replaced by a new bit. By changing the connection of the teeth on the holder shank with the serrations in the lug bore the annular position of the bit with re- 55

- spect to the bit block may be changed as desired. The same is made reversible simply by changing the end-for-end position of the bit holder with respect to the bit block lug, the bit block being of a symmetrical design to receive the latter at either end thereof. Other manners of use and advantages of the improved cutter chain structure will be clearly apparent to those skilled in the art.
- 10 While there is in this application specifically described one form which the invention may assume in practice, it will be understood that this form of the same is shown for purposes of illustration and that the invention may be modified and embodied in various other forms without departing from its spirit or the scope of the appended claims.
- What I claim as new and desire to secure by Letters Patent is:
- 20 1. In a cutter chain, a chain block, a reversible cutter bit having its body formed with a pair of distinct spaced cutting points at each end thereof, all of said cutting points projecting from the bit body in the same direction, and bit holding means for holding said cutter bit in position on said chain block with a pair of said cutting points projecting in cutting position from said chain block, said cutter bit being reversible end for end with respect to said holding means to dispose said other pair of cutting points in cutting position with respect to said chain block.
- 25 2. In a cutter chain, a chain block, a reversible cutter bit having at each end thereof a pair of distinct spaced cutting points, all of said cutting points formed on the same side of said bit, and bit holding means for holding said bit in position on said chain block with a pair of said cutting points projecting in cutting position from said chain block, said bit being reversible end for end with respect to said holding means to dispose the other pair of cutting points in cutting position with respect to said chain block.
- 30 3. In a cutter chain, a chain block, a reversible cutter bit having a body of generally V-shape cross section having at each end thereof a pair of cutting points, the points formed on each leg of the V, and bit holding means for holding said cutter bit in position on said chain block with a pair of said cutting points projecting in cutting position from said block, said cutter bit being reversible end for end with respect to said holding means to dispose the other pair of cutting points in cutting position with respect to said chain block.
- 35 4. In a cutter chain, a chain block, a reversible cutter bit of generally V-shape cross section having a pair of cutting points formed at each end thereof at the same side of the bit body, and bit holding means for holding said cutter bit in position on said chain block with a pair of cutting points projecting in cutting position from said block, said cutter bit being reversible end for end with respect to said holding means to dispose the other pair of cutting points in cutting position with respect to said chain block.
- 40 5. A cutter bit having a body provided with spaced side portions having parallel front edges, the opposite ends of each edge having cutting portions formed thereon, two distinct spaced cutting portions at each end of the body and each cutting portion having a rearwardly and inwardly inclined rear surface.
- 45 6. A cutter bit having a body provided with spaced portions having parallel front edges, the opposite ends of each edge having cutting portions formed thereon, two distinct spaced cutting

tions formed thereon, two distinct spaced cutting portions at each end of the body at the same side of the body and each cutting portion having a rearwardly and inwardly inclined rear surface.

5

7. A cutter bit having its body formed with side spaced portions provided with parallel front edges each terminating in a cutting portion individual thereto at each end of the bit, two cutting portions at each end of the body, and each cutting portion having a rearwardly and inwardly inclined rear surface.

8. A cutter bit having a body of generally V-shape cross section having at each end a pair of spaced cutting points and each cutting point having a rearwardly inclined receding surface.

9. A cutter bit having a body formed with four distinct spaced cutting points, a pair at each bit end, and each pair of cutting points projecting in the same direction from the bit body and each cutting point having a rearwardly inclined receding surface.

10. A bit holder formed of mating parts, each having a recess, the recesses cooperating to form a socket of generally V-shape for receiving a cutter bit of generally V-shape cross section.

11. A stamped metal bit bent into shape with its sides in angularly disposed relation and having cutting points at the ends of its angularly disposed sides and each cutting point having a rearwardly inclined receding surface.

12. In a cutter chain, a bit block having a centrally located lateral lug, the lug having a longitudinal bore, a bit holder having a shank receivable in said lug bore, a forwardly projecting portion having a bit receiving socket, a cutter bit receivable in said socket and having a pair of spaced cutting points, and means engageable with the holder shank for clamping said bit against the forward face of said lug with said spaced cutting points projecting in cutting position from said block lug.

13. In a cutter chain, a bit block having a centrally located lateral lug, the lug having a longitudinal bore, a bit holder having a shank receivable in said lug bore, a forwardly projecting portion having a bit receiving socket, a cutter bit receivable in said socket, and means engageable with the holder shank for clamping said bit against one end face of said lug, said holder being reversible end for end with respect to said lug for clamping said cutter bit adjacent the opposite end face of said lug to reverse the position of the bit on the bit block.

14. A cutter bit having at each end thereof a pair of spaced cutting points at the extremities of similar tapering projections, the body of said bit between said projections cut back so that each cutting point is formed at the junction of a straight surface connecting points at opposite ends of the bit and an oblique surface left by the cutting away specified.

15. A cutter bit having four cutting points disposed at the corners of a rectangle and having a body two of whose sides follow sides of such rectangle and deeply notched between the pairs of points respectively at the opposite ends of said sides.

16. A cutter bit having a body formed at each end with a pair of spaced projections, the inner edges of which extend along lines converging at the longitudinal center of the bit, and parallel lateral edges, the inner converging edges of the projections and said parallel edges terminating

75

in cutting points at the extremities of said spaced projections.

17. A cutter bit having a body formed at each end with a pair of spaced projections, the inner edges of which extend along lines converging at the longitudinal center of the bit, and parallel lateral edges, the inner converging edges of the projections and said parallel edges terminating in cutting points at the extremities of said spaced

projections, the rearward surfaces of said projections inclined inwardly and rearwardly.

18. A double-ended cutter bit having a body in the shape of a trapezoid viewed in side elevation and having parallel sides and relatively inclined ends, said body formed with a pair of distinct spaced cutting points at each end thereof. 5

WARREN NOBLE.

CERTIFICATE OF CORRECTION.

Patent No. 2,121,043.

June 21, 1938.

WARREN NOBLE.

It is hereby certified that the name of the assignee in the above numbered patent was erroneously described and specified as "Sullivan Machine Company" whereas said name should have been described and specified as Sullivan Machinery Company, a corporation of Massachusetts, as shown by the record of assignments in this office; and that the said Letters Patent should be read with this correction therein that the same may conform to the record of the case in the Patent Office.

Signed and sealed this 2nd day of August, A. D. 1938.

Leslie Frazer,

Acting Commissioner of Patents.
